UNITED STATES PATENT OFFICE.

STANLEY H. LYONS, OF PROVIDENCE, RHODE ISLAND.

DESIGN FOR A RING.

51,864.

Specification for Design. Patented Mar. 12, 1918.

Application filed December 15, 1917. Serial No. 207,376. Term of patent 3½ years.

To all whom it may concern:

Be it known that I, STANLEY H. LYONS, a citizen of the United States, residing at the city and county of Providence, State of Rhode Island, have invented a new, original, and ornamental Design for a Ring, of which the following is a specification, reference being had to the accompanying drawing, forming part thereof.

Figure 1— is a view of the front of a ring illustrating my new design.

Fig. 2— is a perspective view of a ring showing one of the groups of figures as extending down the side of the ring.

I claim:

The ornamental design for a ring, as shown.

STANLEY H. LYONS.

Witnesses:

A. J. Moss,
M. A. KEEFE.
